UNITED STATES PATENT OFFICE.

AMOS BARNES, OF DETROIT, MICHIGAN, ASSIGNOR TO JAMES GAMBLE AND JOHN M. BREWER, OF SAME PLACE.

MATCH-SAFE.

SPECIFICATION forming part of Letters Patent No. 596,316, dated December 28, 1897.

Application filed March 6, 1897. Serial No. 626,185. (No model.)

To all whom it may concern:

Be it known that I, AMOS BARNES, a citizen of the United States, residing at Detroit, county of Wayne, State of Michigan, have 5 invented certain new and useful Improvements in Match-Safes; and I declare the following to be a full, clear, and exact description of the invention, such as will enable others skilled in the art to which it pertains to make 10 and use the same, reference being had to the accompanying drawings, which form a part of this specification.

My invention relates to match-safes; and it consists in improved means for delivering a 15 single match at each operation of the delivering mechanism of the safe.

My invention is shown in the accompanying drawings, in which—

Figure 1 is a vertical longitudinal section. 20 Fig. 2 is a view showing the form of the roll for delivering the match.

In the drawings, A is the base, having a concave portion a, on which the match drops when delivered.

25 C is a roll mounted in the sides of the frame. This roll is provided with a longitudinal groove c, and is substantially like the roll shown in my prior applications, Serial Nos. 604,398 and 585,867, except that the rear wall 30 of the groove c is at its maximum height at the center and recedes toward each end until it reaches the level of the bottom of the groove at the ends. This construction is to overcome a difficulty experienced with the former 35 constructions, in which one end of a match would catch in a groove at the end when the roll would draw the match around at an angle across the roll. The construction shown herein obviates that difficulty. The roll is also 40 provided forward of the groove with a series of annular ribs c² c², which have their greatest depth immediately above the groove and recede to the body of the roll, as shown in the drawings.

45 D is the front of the match-safe, and is pivoted in the frame at d and allowed a slight swinging movement. It is provided at the lower edge with teeth or fingers, which enter between the annular ribs c² c² on the roll C

and form a drag over the surface of the roll 50 as it is operated.

E is the inclined bottom of the match-safe and is rigidly supported in the frame. This bottom comes down on an incline to a point directly over the longitudinal groove in the 55 roll and is then offset at right angles at e. The lower edge of the offset portion e I prefer to provide with a right-angled portion e', which last-named portion comes directly over the roll. This portion e' forms a narrow ledge 60 that will pass under a match as the roll comes back, and in conjunction with the portion e will straighten it and leave it parallel with the roll. The portion e forms a wall back of the matches that have dropped onto the roll, 65 and this present device differs in that respect from my prior applications. In the former applications this wall was absent, and the matches were forced back into the body of the safe into and against the mass of matches 70 resting therein. The construction of this device is such that the space between the drag front D and the wall e is an additional chamber or cavity, in which the matches are straightened out and forced into a position 75 parallel to one another. When the roll is in its normal position and the safe filled with matches, a few of the matches drop down over the end of the inclined portion of the bottom between the wall e and the drag front, 80 the matches being approximately parallel. When the roll is operated, one of the matches drops into the longitudinal groove and is carried forward and delivered from the safe, while the remaining matches in the space 85 over the roll ride over the roll and are carried back by the ribs c² c² and the lower one drops or rolls into the groove, the operation being practically the same as in former devices.

What I claim is—

1. In a match-safe, a delivery-roll provided with a longitudinal groove, the rear wall of which is of the maximum height at the center and receding toward the ends, substantially as described.

2. In a match-safe, the combination of the frame, a roll mounted in the frame provided with a longitudinal groove, an inclined bot-

90

95

tom, and a depending wall over the groove at the end of the bottom, having its surfaces at right angles to the surface of the roll whereby the matches carried back by the roll 5 when returned will be forced against the depending wall and straightened out, substantially as described.

3. In a match-safe, the combination of the frame, the roll provided with a longitudinal 10 groove mounted in the frame, the inclined

bottom and depending wall at the end of the bottom over the roll provided with the right-angled edge c' , substantially as described.

In testimony whereof I sign this specification in the presence of two witnesses.

AMOS BARNES.
